UNITED STATES PATENT OFFICE.

WARREN B. HARRIS, OF MILLBURY, MASSACHUSETTS.

DOBBY-CHAIN.

1,199,546.

Specification of Letters Patent. Patented Sept. 26, 1916.

Application filed February 19, 1915. Serial No. 9,424.

To all whom it may concern:

Be it known that I, WARREN B. HARRIS, a citizen of the United States, residing at Millbury, in the county of Worcester and 5 Commonwealth of Massachusetts, have invented a new and useful Improvement in Dobby-Chains, of which the following, together with the accompanying drawings, is a specification.

- 10 The present invention relates to an improved construction for dobby or pattern chain, such as is used in various types of weaving machinery for controlling the pattern of the cloth being made by the machine.
- 15 The features of the invention are fully set forth in the following description and pointed out in the annexed claims, reference being had to the accompanying drawings, in which—
- 20 Figure 1 is a plan view of a short section of chain made in accordance with my invention. Fig. 2 is a section on line 2—2, Fig. 1, and Fig. 3 is a plan view of a single link or bar of chain of a slightly different type, 25 showing the application of my invention thereto.

Similar reference characters refer to similar parts in the different figures.

The ordinary types of dobby or pattern 30 chains comprise a series of pivotally connected links, in the form of more or less elongated wooden bars, arranged side by side, with their longitudinal edges opposing, and their corresponding ends in alinement. It is common practice to connect adjacent bars of the series by a short chain link at each end, said link being attached to suitable eyelets projecting from the opposing edges of adjacent bars. An ordinary 35 expedient for conveniently forming and attaching such eyelets consists in inserting a wire transversely through the bar at each end, and then looping each free end of said wire around into substantial contact with the edge of the bar, thereby forming two 40 eyes from a single wire, the centers of which are in alinement with the line of travel of the chain and are slightly offset from the central transverse portion of the wire which 45 is embedded in the bar.

An objection to eyelets formed in the manner above described is found in the tendency of the wire to twist around in the bar; this results in a displacement of the 50 eyelets of one bar from alinement with the eyelets of adjacent bars, causing said bar to

shift longitudinally with respect to the other bars, and thereby prevent the accurate traverse of the chain over its drums.

My invention contemplates the elimination of the difficulty above set forth, by providing a construction in which the wires are prevented from turning in the bars, and the same will now be described with particular reference to the drawings.

The bars 1, 1 of the chain shown in Figs. 1 and 2 are of the ordinary form of single index chain bars, each presenting a single row of holes 2, 2 for the insertion of pins 3, 3 which determine the pattern of the cloth 70 in the usual manner. The drums, not shown, over which the chain passes at each end of its traversing movement, afford longitudinal grooves on their peripheries, of the same cross-sectional shape as the bars and spaced 75 apart the same distance as adjacent bars of the chain; to facilitate the entrance and exit of the bars to and from said grooves, the longitudinal side walls of the grooves are beveled, and the longitudinal side edges 4, 4 of the bars are correspondingly beveled, converging toward the under face of the bar, i. e., the face which moves into contact with the peripheries of the drums.

At each end of each bar 1 a wire 5 is inserted transversely therethrough, and said wire projects outwardly from each inclined side edge 4 of the bar a sufficient distance to enable the end of the same to be looped around to form an eyelet. The end of the wire 5 projecting from one side edge 4 of the bar is given a slight lateral deflection or offset, as shown at 6, and the other end of said wire, projecting from the other side edge 4 is given the same offset in the opposite direction, as shown at 7. The two free ends of the wire are then looped around in directions opposite to their respective offsets, and therefore in relatively opposite directions to each other, into contact with the 105 surface of their corresponding side edges, to form eyelets 8 and 9 respectively. By reason of the offsets 6 and 7 the centers of the two eyelets 8 and 9 are caused to coincide with the axial line of the straight central portion of the wire 5 which is embedded in the bar 1. All the bars of the chain are thus provided with eyelets 8 and 9 at each end; the chain is assembled, as shown in Fig. 1, by connecting opposing eyelets of adjacent bars by short links 10, in the usual manner.

It will be seen, that by reason of the opposite inclination of the side edges 4, 4 of a bar, the contact therewith of the oppositely bent free ends of the wire 5 precludes any tendency of the eyelets thus formed to turn about the axis of the straight central portion of the wire; taking an eyelet 8, for example, the tendency of the same to twist in a clockwise direction, Fig. 1, is resisted by the body 10 of the bar 1 interposed, by reason of the inclination of the edge 4, in the way of the extreme end of the wire forming such eyelet, and its tendency to twist in the opposite direction is prevented in the same way by the inability of the extreme end of the eyelet 9 of the same wire to turn farther in this opposite direction.

Referring to Fig. 3, the bar 11 therein shown is of the double index type, presenting the rows of staggered holes 12, 12 for the reception of the pattern pins. Owing to the very small distance, measured longitudinally of the bar, between holes in different rows, great difficulty is experienced in passing a wire at right angles through the bar, without breaking into one of the holes 12 on either side of the same. I propose to dispose the wires 13 at oblique angles to the longitudinal axis of the bar, as shown in Fig. 3, thereby giving considerable clearance between said wires and the holes 12, 12 on each side thereof. This arrangement is peculiarly adapted to the carrying out of my invention with respect to the looping of the free ends of each wire in opposite directions, since no offsetting or deflection of the wire emerging from the beveled side edges 14, 14 of the bar is required, in order to bring the centers of the eyelets 15 and 16 thus formed, into alinement with each other and with the line of movement of the chain.

It will be clear that a chain having bars made in the manner just described, and connected up with the ordinary links 17 possesses the same advantages of operation as the chain shown in Fig. 1.

I claim,

1. In a device of the character described, a series of linked bars having oppositely beveled edges, each bar having a member extended therethrough and bent into eyelet form at each end, the free ends of said member terminating in substantial contact with

the adjacent edges of the bar on opposite sides of the axis of said member.

55

2. In a device of the character described, a series of linked bars having oppositely beveled edges, each bar having a member extended therethrough and bent into eyelet form at each end, the free ends of said member terminating on opposite sides of the axis of said member, and in substantial contact with the adjacent edge of said bar.

60

3. In a device of the character described, a series of linked bars having oppositely beveled edges, each bar having a member extended therethrough, with the free ends of said member bent around, in opposite directions, into substantial contact with the adjacent edge of the bar.

70

4. In a device of the character described, a bar providing oppositely beveled edges, and a member extended through said bar and projecting from each of said edges, the free ends of said member being bent around into substantial contact with their adjacent edges on opposite sides of the axis of said member.

75

5. In a device of the character described, a bar providing oppositely beveled edges, having a member extended therethrough and bent into eyelet form at each end, said beveled edges of the bar coöperating with the free ends of said member to prevent the turning of said member in the bar.

85

6. In a device of the character described, a bar providing oppositely beveled edges, and a member extended obliquely through said bar, and projecting from each of said edges, the free ends of said member being bent around in reverse directions into contact with the adjacent beveled edges of the bar to form eyelets.

90

7. In a device of the character described, a series of bars adapted to be linked together, each bar having a member extended obliquely therethrough and bent in reverse directions into eyelet form at each end, the free end of said member terminating on opposite sides of the axis of said member and in substantial contact with the adjacent edge of said bar.
